[57] CLAIM

The ornamental design for a fluid delivery unit, as shown and described.

DESCRIPTION

FIG. 1 is a perspective view of a fluid delivery unit showing our new design;

FIG. 2 is a front elevation view thereof;

FIG. 3 is a top view thereof;

FIG. 4 is a left side elevation view thereof;

FIG. 5 is a right side elevation view thereof;

FIG. 6 is a rear elevation view thereof; and

FIG. 7 is a bottom view thereof.

FIG. 8 is a perspective view of a fluid delivery unit showing an alternative embodiment of our new design;

FIG. 9 is a front elevation view thereof;

FIG. 10 is a top view thereof;

FIG. 11 is a left side elevation view thereof;

FIG. 12 is a right side elevation view thereof;

FIG. 13 is a rear elevation view thereof; and,

FIG. 14 is a bottom view thereof.
